JOSEPH MOLKENTHIN, JR., OF NEWARK, NEW JERSEY, ASSIGNOR TO CLARK BLADE & RAZOR COMPANY, OF NEWARK, NEW JERSEY, A CORPORATION OF NEW JERSEY.

SAFETY-RAZOR.

1,146,945.

Specification of Letters Patent. Patented July 20, 1915.

Application filed November 5, 1914. Serial No. 870,395.

To all whom it may concern:

Be it known that I, JOSEPH MOLKENTHIN, Jr., a citizen of the United States, and a resident of Newark, county of Essex, and State 5 of New Jersey, have invented certain new and useful Improvements in Safety-Razors, of which the following is a specification.

My invention relates to safety razors, and more especially to razors of the well known 10 hoe type in which removable and replaceable blades are held in a suitable holder, which permits of all the blades being removed and replaced as desired. In such razors it is common to obtain the holding action for 15 securing the blade in place by screwing on the handle, and, for example, in my former Patent No. 1,005,273, of which this is an improvement, the blade has been pushed upward against retaining members by the end 20 of the handle upon screwing the latter in place. Unless the screw-threaded shank on the end of such handle is formed of exactly the right length to secure the proper holding action the blade is liable either to be 25 insecurely held or to be bent upward in its middle and put under a tension which may result in its breakage. Furthermore, in such construction, as the extent to which the threaded shank on the end of the handle 30 may be screwed up is determined only by the shoulder at the end of such screw-threaded shank, it becomes essential that the threads of the screw-threaded handle shank be formed with accuracy and precision right 35 up to the shoulder. Furthermore, in my said patent, and in many other safety razor holders, according to the art in practice up to the present, the blade is freed upon the handle being unscrewed, so that it can readily drop out, and care has to be exercised in 40 holding the parts so that when the handle is unscrewed the blade will not drop out and be injured or inflict injury. Furthermore, with such construction it is necessary 45 that the blade be removed from its holder after use to permit the cleaning of lather and hairs from between the blade and guard where they are collected in the act of shaving.

According to my present invention a safety razor blade holder is produced in

which the disadvantageous features referred to are not present; the blade is initially positioned in one member of the holder and can not drop out, but remains in place therein 55 whether the handle be screwed in place or not, and there is no occasion or opportunity for bending and breaking the blade by screwing the handle too far or too tight; the screw-threaded portion of the handle which 60 is made use of in the holding operation is at some little distance from the shoulder at its inner end so that there is no necessity of accurately and carefully forming the screw threads on the shank right up to the 65 shoulder.

According to the present invention there is further provided means for positioning the blade on its carrying member so that when brought into contact with the member 70 upon which the guard is separately formed it will register therewith and will not require further positioning or attention. Furthermore, the guard member and the blade carrying member of the present invention 75 are pivoted together so that it becomes unnecessary to remove the blade after each use, and the guard and holder may be readily cleaned without removing the blade, which may be retained in place in the 80 holder until it gets dull and must be replaced by a new blade.

With the foregoing and related objects in view, my invention consists in the parts, improvements and combinations herein set 85 forth and claimed.

In order that my invention may be clearly understood I have shown one embodiment thereof in the accompanying drawing forming a part of this specification, but it is to 90 be understood that the same is shown for the purpose of illustration only and that my invention is not confined to the specific form shown.

In the said drawings, wherein the same 95 reference characters are applied to designate the same parts throughout, Figure 1 is a top plan view of a razor embodying my invention and showing a blade in position therein. Fig. 2 is a top plan view of the holder with 100 the blade removed. Fig. 3 is a view in side elevation of a razor embodying my inven-

tion and having the blade therein, and Fig. 4 is a view taken from the same direction as Fig. 3, but partly sectional, the sectional portion being taken on the line 4-4, Fig. 1, 5 and also showing an adjusted position of the blade carrying member of the holder in dotted lines.

The reference numeral 10 is applied to 10 designate the head of the holder generally, and the handle is shown at 11. The head of the holder comprises two parts which are pivoted together, namely, the blade carrying, positioning and retaining member 12, and the co-acting member 13 which carries 15 the guard for the cutting edge of the blade. These two members 12 and 13 are pivoted together, as shown at 14, upstanding stiffening flanges 15 terminating in ears 15' being provided for this purpose on each end of 20 the member 13, and the ears 15' being furnished with apertures 16 in which are received the pivot studs 17 on the member 12.

The member 12 preferably comprises a 25 generally flat plate 18 which is provided with means for receiving and positioning a properly formed blade and for carrying the same when inserted therein until purposely withdrawn, and for clamping the same in position upon the second member 13 of the 30 holder. In the form shown such means comprises upwardly and inwardly turned hooks 19, 19, formed at each end of the blade and having projecting end portions 20, 20 which extend beyond the forward 35 edge 21 of the plate 18 and above portions of the member 13. Such projecting end portions are preferably bent downward slightly at their extremities, as shown at 22. The plate 18 is also preferably provided with 40 additional blade holding and positioning members which, as shown, have the form of upwardly and inwardly extending hooks 23, 23 at each end thereof which, like the hook portions 19, 19, are preferably formed 45 integral with the plate 18. These hook portions 23, 23 are preferably provided with rearwardly extending projections 23^a, 23^a to contact with suitable positioning means provided on the blade, and by co-action there- 50 with to position the blade and to determine the extent of projection of its cutting edge beyond the forward edge 21 of the plate 18. The hook members 23, 23 being formed with extensions 23^a, 23^a clear the ears 15' of the 55 member 13 and permit free pivotal movement of the members 12 and 13. The pivot studs 17 are also preferably formed integral with the plate 18, and said plate 18 is preferably provided with an integral down- 60 wardly extending rear flange 24 to stiffen and strengthen the member 12. Said plate 18 of member 12 is also provided, preferably at about its central portion, with an opening 25 which is interiorly screw-threaded to re- 65 ceive the screw threads upon the end of the

handle 11, and such plate 18 is preferably downwardly recessed about the opening 25, as shown at 26, in order that the screw-threaded end of the handle need not be unduly long.

The member 13 of the holder is provided with an opening 27 in line with the opening 25 of the member 12, and the metal of the member 13 is preferably recessed or upset somewhat, as shown at 28, about the opening 70 27, such upset part being preferably slightly out of line with the principal portion of the member 13, as shown, in order to provide a proper cutting angle for the blade and at the same time to accommodate a square shoulder on the handle 11. The member 13 is provided at its forward edge with suitable guard members, such as the teeth 29, and is also provided with means for preventing injury to the face by the corners of the blade, the means provided for this purpose comprising upstanding studs or projections 30, 30 formed on the guard teeth at each end of the guard member.

Immediately behind and preferably in 90 line with the bases of the guard teeth 29 the member 13 is provided with a longitudinally extending surface 31, upon which the blade 32 may rest and against which it may be held by the projections or tongues 20 95 upon the hooks 19 of the member 12. Such guard fingers 29 and the blade supporting part 31 of the member 13 are preferably elevated somewhat above the remainder of the member 13 to register with the plate 18 of 100 the member 12 and at the same time to permit the recessing of the members 12 and 13 about the openings 25 and 27 as already described.

The blade 32 is provided with means for 105 co-acting with the positioning members 23, 23 and for thereby determining the extent of its projection at the cutting edge beyond the forward edge of the plate 18. In the form shown the thin removable blade is provided with the customary backing 33, which backing is cut away, as shown at 34, 34, and shoulders 35, 35 are formed therein to contact with the projections 23^a, 23^a on the hooks 23, 23, and to thereby accurately position the 110 blade in place so that the same may extend beyond the member 12 to an extent just sufficient to cause the corners at the cutting edge to rest immediately behind the outwardly projecting guard members 30, 30 and 115 without coming into contact therewith, thus giving the correct position of the blade for 120 shaving.

The members 12 and 13 being loosely pivoted together and not in contact at the forward edge, the blade 32 is inserted by resting it upon the plate 18 and sliding it forward with its ends beneath the retaining hooks 19 and 23 until the shoulders 35, 35 come into contact with the positioning members 23, 23. 125 130

This operation is easily performed and without the danger of injuring the blade which is always present when the blade is inserted over the guard and in contact therewith. 5 The blade, being held between the plate 18 and the hooks 19 and 23, will be retained in place upon the member 12 unless purposely withdrawn therefrom, so that there is no chance of the blade dropping out when the 10 parts of the holder are disassembled, and no need to remove it in order to clean the holder. After the blade is inserted the member 12 is turned on its pivots into contact with the member 13, and the handle 11, having 15 a shoulder 36 and a screw-threaded end portion 37, is inserted through the opening 27 and screwed into the screw-threaded opening 25 in the member 12. In this manner the members 12 and 13 are drawn together, so that the projections 20, 20 of the 20 hooks 19, 19 rest upon the blade supporting portion 31 of the member 13 with the blade interposed, which supporting portion 31 is preferably placed immediately behind the 25 projecting teeth or guard 29 and extends longitudinally of the member 13 through its entire length.

It will be seen that with the arrangement that has been described the blade is held and 30 accurately positioned upon the member 12 and in place thereon, and that it will be retained by the member 12 whether the parts are assembled with the handle in place or not; that the screw thread 37 need not be 35 cut with accurate precision up to the shoulder 36 since it does not enter a screw-threaded opening in the immediate neighborhood of such shoulder; that the blade can always be clamped securely in place irrespective of 40 the precise length of the screw-threaded shank 37 beyond the shoulder 36; that there is no chance for the blade being broken by undue pressure in screwing up the handle, such pressure not resulting in any bending 45 of the blade, but merely resulting in increased pressure between the members 12 and 13, the blade lying flat between them, and, if the plate 18 is bent by screwing up the handle especially tight such bending 50 does not extend to the blade, but the plate 18 is bent beneath the blade which can remain flat and unbent; and that numerous other features of advantage and increased utility are obtained.

55 It is to be understood that modifications and substitution of equivalents may be made in the precise structure shown within the scope of my claims and without departing from my invention or sacrificing any of the 60 advantages thereof.

Having thus described my invention, I claim:

1. In a safety razor, a blade holding plate, hooks on its upper surface to hold and position a blade in place thereon, said plate

being depressed at one part and provided with a screw-threaded opening thereat, a separate guard member, and a screw-threaded handle for entering said aperture and drawing said plate down on said guard member, substantially as set forth. 70

2. In a safety razor, a plate having hooks for holding a blade thereon, said plate being further provided with top hooks formed with rear stops thereon, a blade having a 75 backing and shoulders in said backing to co-operate with said stops and position the blade on said plate, a separate guard member to which said plate is pivoted, studs on the ends of the guard member and disposed 80 so that they protect the corners of the edge of the blade when the plate is swung into position, and means extending through the guard member to draw the plate and a blade held thereby down upon the guard member, 85 substantially as set forth.

3. In a safety razor, a holder comprising two parts pivoted together, the first of said parts having means to hold and position a blade upon the upper surface thereof, the 90 second of said parts comprising a guard for the cutting edge of the blade, said parts being provided with registering openings, that in the lower part being unthreaded, 95 and that in the upper part being threaded, and a handle having a threaded end inserted at the first named opening and screwed in the second named opening to hold the parts together and to draw a blade held by the upper part of the holder down upon the 100 guard of the lower part of the holder, substantially as set forth.

4. In a safety razor, a guard member provided with end flanges and upwardly extending perforated ears and having a blade 105 supporting portion and guard finger extending upwardly at one edge, said member being provided with a substantially central opening, a blade holding member pivoted in said ears and provided with means for holding and positioning a blade in its upper surface and having a screw-threaded opening registering with the opening in the first named member, and a handle comprising a shoulder and a screw-threaded part beyond 110 said shoulder and adapted when inserted in the opening in the first member to screw in the opening in the second member and hold the parts in place, substantially as set forth. 115

5. In a safety razor, a guard member provided with upwardly extending perforated ears at its ends and having a raised blade supporting portion and guard finger at the front edge, the member having an opening in rear of said raised portion, a blade holding member pivoted in said ears and having its front too short to engage the raised portion of the guard member, hooks on the blade holding member extending forward so as to swing down on the blade supporting 125 120 130 135 140 145 150 155 160 165 170 175 180

portion of the guard member, a blade held between the bottom part and the hooks of the blade holding member and acting to limit the swinging of said last mentioned member by engaging the blade supporting portion of the guard member, the blade holding member having a screw-threaded opening registering with the opening in the guard member, and a handle comprising a shoulder and a screw-threaded part beyond

said shoulder to engage the screw-threaded opening in the blade holding member.

In testimony that I claim the foregoing, I have hereunto set my hand, this 20th day of October, 1914.
